[57] CLAIM

The ornamental design for a comb, as shown and described.

DESCRIPTION

FIG. 1 is a top plan view of a comb embodying my design;

FIG. 2 is a front elevational view thereof;

FIG. 3 is an enlarged fragmentary top plan view thereof;

FIG. 4 is an enlarged cross sectional view taken on line 4—4 of FIG. 2;

FIG. 5 is an enlarged fragmentary plan view, as seen from the bottom of FIG. 8;

FIG. 6 is an enlarged fragmentary plan view as seen from the bottom of FIG. 9;

FIG. 7 is an enlarged cross sectional view taken on line 7—7 of FIG. 8;

FIG. 8 is an enlarged fragmentary elevational view of the left hand portion of FIG. 2;

FIG. 9 is an enlarged fragmentary elevational view of the right hand portion of FIG. 8;

FIG. 10 is an enlarged right end elevational view thereof; and

FIG. 11 is an enlarged left end elevational view thereof.
